[57] CLAIM

The ornamental design for a coin sorting machine, shown and described.

DESCRIPTION

FIG. 1 is a front perspective view of a coin sorting machine showing my new design;

FIG. 2 is a bottom perspective view thereof;

FIG. 3 is a right side elevational view thereof;

FIG. 4 is a left side elevational view thereof;

FIG. 5 is a bottom plan view thereof;

FIG. 6 is a rear elevational view thereof;

FIG. 7 is a front elevational view thereof;

FIG. 8 is a top plan view thereof;

FIG. 9 is a front perspective view of a second embodiment of a coin sorting machine showing my new design the only difference being the transparent front cover;

FIG. 10 is a bottom perspective view thereof;

FIG. 11 is a right side elevational view thereof;

FIG. 12 is a left side elevational view thereof;

FIG. 13 is a bottom plan view thereof;

FIG. 14 is a rear elevational view thereof;

FIG. 15 is a front elevational view thereof; and,

FIG. 16 is a top plan view thereof.
